(57) **CLAIM**

We claim the ornamental design for seating unit, as shown and described.

DESCRIPTION

FIG. 1 is a front perspective view of a modified seating unit shown in our design;

FIG. 2 is a left side view of FIG. 1, the right side being a mirror image of the left side;

FIG. 3 is a front view of FIG. 1;

FIG. 4 is a back view of FIG. 1; and,

FIG. 5 is a top view of FIG. 1.

In the drawings, the broken line showing of an adjustment handle depicts environmental subject matter and forms no part of the claimed design.
